(57) **CLAIM**

The ornamental design for a surface cleaner, as shown and described.

DESCRIPTION

FIG. 1 is a right, front perspective view of a first embodiment of a surface cleaner according to my novel design;

FIG. 2 is a left, front perspective view of the first embodiment of the surface cleaner according to my novel design;

FIG. 3 is a front view of the first embodiment of the surface cleaner according to my novel design;

FIG. 4 is a left side view of the first embodiment of the surface cleaner according to my novel design;

FIG. 5 is a right side view of the first embodiment of the surface cleaner according to my novel design;

FIG. 6 is a top view of the first embodiment of the surface cleaner according to my novel design;

FIG. 7 is a rear view of the first embodiment of the surface cleaner according to my novel design;

FIG. 8 is a bottom view of the first embodiment of the surface cleaner;

FIG. 9 is a front perspective view of a first embodiment of the surface cleaner according to my novel design and including a handle in broken lines for illustrative purposes only;

FIG. 10 is a right, front perspective view of the second embodiment of the surface cleaner according to my novel design;

FIG. 11 is a left, front perspective of the second embodiment of the surface cleaner according to my novel design;

FIG. 12 is a front view of the second embodiment of the surface cleaner according to my novel design;

FIG. 13 is a left side view of the second embodiment of the surface cleaner according to my novel design;

FIG. 14 is a right side view of the second embodiment of the surface cleaner according to my novel design;

FIG. 15 is a top view of the second embodiment of the surface cleaner according to my novel design;

FIG. 16 is a rear view of the second embodiment of the surface cleaner according to my novel design;

FIG. 17 is a front perspective view of the of the second embodiment of the surface cleaner according to my novel design and including a handle in broken lines for illustrative purposes only;

FIG. 18 is a right, front view of a third embodiment of the surface cleaner according to my novel design;

FIG. 19 is a left, front view of the third embodiment of the surface cleaner according to my novel design;

FIG. 20 is a front side view of the third embodiment of the surface cleaner according to my novel design;

FIG. 21 is a left side view of the third embodiment of the surface cleaner according to my novel design;

FIG. 22 is a right side view of the third embodiment of the surface cleaner according to my novel design.

FIG. 23 is a top view of the third embodiment of the surface cleaner according to my novel design.

FIG. 24 is a rear view of the third embodiment of the surface cleaner according to my novel design; and,

FIG. 25 is a front perspective view of the third embodiment of the surface cleaner according to my novel design and including a handle in broken lines for illustrative purposes only.

The broken lines are for illustrative purposes only and form no part of the claimed design.
